UNITED STATES PATENT OFFICE.

EDWARD WESTON, OF NEWARK, NEW JERSEY.

DESIGN FOR A CASE FOR ELECTRICAL MEASURING-INSTRUMENTS.

SPECIFICATION forming part of Design No. 22,101, dated January 3, 1893.

Application filed December 7, 1892. Serial No. 454,406. Term of patent 14 years.

To all whom it may concern:

Be it known that I, EDWARD WESTON, of Newark, Essex county, New Jersey, have invented and produced a new and original Design for Cases for Electrical Measuring-Instruments, of which the following is a specification.

My design consists in the configuration of the case substantially as herein after described.

Figure 1 is a side view of the said case and Fig. 2 is a front view.

Similar letters of reference indicate like parts.

The lower portion, A, of the case is rounded in front and has parallel sides, B. Above the part A, the case has a cylindrical portion, C.

Above the cylindrical portion the case appears closed, and its upper surface, D, is flat, or nearly so. Above the upper surface D appears a sector-shaped portion, E, the thickness of said sector-shaped portion, as shown in Fig. 1, being less than the diameter of the cylindrical part C.

I claim as my invention

The design for the case for an electrical measuring instrument substantially as herein shown and described

EDWARD WESTON.
